R. B. KINGMAN

SCOURING IMPLEMENT

Filed May 14, 1924

UNITED STATES PATENT OFFICE.

RUSSELL B. KINGMAN, OF ORANGE, NEW JERSEY, ASSIGNOR TO THE CHORE-UTENSILS CORPORATION OF AMERICA, OF WEST ORANGE, NEW JERSEY, A CORPORATION OF NEW JERSEY.

SCOURING IMPLEMENT.

Application filed May 14, 1924. Serial No. 713,182.

To all whom it may concern:

Be it known that I, RUSSELL B. KINGMAN, a citizen of the United States, residing at Orange, in the county of Essex and State 5 of New Jersey, have invented certain new and useful Improvements in Scouring Implements; and I do hereby declare the following to be a full, clear, and exact description of the invention, such as will enable 10 others skilled in the art to which it appertains to make and use the same, reference being had to the accompanying drawings, and to characters of reference marked thereon, which form a part of this specification.

15 This invention relates, generally, to an improved kitchen utensil or scouring implement; and the invention has reference, more particularly, to an improved construction of kettle, pot and pan scouring device.

20 The invention has for its principal object to provide an article of the kind above mentioned, which consists of an abrading element preferably made of a metallic fabric rolled upon itself to form a spongiform 25 mass, a handle member, and a novel means for securely fastening the abrading element to the handle member.

Other objects of this invention, not at this 30 time more particularly enumerated, will be clearly understood from the following detailed description of the same.

With the various objects of this invention in view, the same consists, primarily, in the novel construction of scouring implement 35 hereinafter set forth; and, the invention consists, furthermore, in the novel arrangements and combinations of the several devices and parts, as well as in the details of the construction of the same, all of which 40 will be more fully described in the following specification, and then finally embodied in the claims appended thereto.

This invention is clearly illustrated in the accompanying drawings, in which:—

45 Figure 1 is a side elevation of the novel scouring implement, made according to and embodying the principles of this invention; Figure 2 is a similar view in part vertical longitudinal section, to show the means of 50 fastening the abrading element to the handle member, this view also showing, in dotted presentation, the abrading element and fastening devices before the same are operatively assembled with the handle mem-

ber; Figure 3 is a top view of the scouring 55 implement; Figure 4 is a similar top view of the scouring implement, showing a slightly modified form of fastening means for operatively assembling the abrading element with the handle member; and Figure 5 is a perspective view of the modified 60 form of fastening means shown in connection with said Figure 4.

Similar characters of reference are employed in all of the hereinabove described 65 views, to indicate corresponding parts.

Referring now, more especially to Figures 1 to 3 inclusive, the reference character 70 6 indicates a handle member, which is preferably made of wood or some similar material. Said handle member 6 is provided with a concave seat or socket 7 at one end, and the exterior of the body of the handle member, at the end possessing said concave seat or socket, is tapered or chamfered, as 75 at 8, to meet the outer margin of the seat or socket 7, and thus form at said margin an acute annular gripping edge 9.

The abrading element is constructed from a tubular knit fabric. This fabric may be 80 all metal, that is, one which is knit from a thin ribbon-like metallic wire or strand, preferably of non-corrosive character, such e. g. as copper; or the fabric may be made of tubular knit yarn, or mixed tubular knit 85 yarn and metal strands to provide a composite material. I prefer to use the all metal tubular knit fabric however, since such a fabric, when made up into a spongiform mass, provides an abrading element 90 producing a maximum of abrading efficiency. In making up the abrading element, I take a suitable length of tubular knit fabric, and roll it endwise upon itself to form, preferably, an annular or ring-like 95 member, which, due to the mesh of the fabric out of which it is thus formed, results in a springy and highly porous or spongiform mass, thereby providing an abrading element 10, which is not only of 100 exceedingly high abrading efficiency, but which is sufficiently yieldable or conformable to a surface against which it is pressed as to effectively engage such surface, even even when the latter is angular or irregular 105 in contour. I do not claim the above described all metal abrading element per se, since the same is already described and

claimed in prior United States Letters Patent No. 1,449,184, dated March 20, 1923. I have found, however, that the use of such an abrading element, particularly when 5 made in small sizes, is rendered much more convenient, if a handle member for manipulating the same is attached thereto, and, therefore, this invention relates to a combination with such, or any other type or shape 10 of, abrading element, of the novel handle member above described and a novel means for securely and effectively attaching the former to the latter.

The novel fastening or attaching means 15 for securing the abrading element 10 to the handle member 6, comprises a metallic keeper plate 11, and a fastener, preferably in the form of a staple 12.

The assembling operations are preferably 20 performed upon a punch press. The handle member 6 is supported in a jig, with the end thereof which possesses the seat or socket 7 upward. The annular abrading element 10 is laid upon the end of the handle member, 25 with its inner circumference overlapping the acute gripping edge 9. The keeper plate 11 is larger in diameter than the diameter of the central opening of the annular abrading element 10, so that its marginal portions 30 overlap the inner circumference of the latter. Preferably the keeper plate 11 is initially provided with an upwardly presented convex center portion, as indicated at 13 in the dotted representation thereof shown in 35 Figure 2. The punch of the punch press is so shaped, as to force or reverse the convex center portion 13 and drive the same downwardly upon the bottom of the concave seat or socket 7 of the handle member 6 to form 40 a depressed seated portion 14, and in so doing causes the marginal portions of the keeper plate 11 to be deformed to provide an annular gripping lip 15, which pinches and tightly grips the inner circumferential 45 portions 16 of the annular abrading element 10 against the acute gripping edge 9 at the margin of the concave seat or socket 7 of the handle member, as shown by the solid lines in Figure 2. To hold the keeper plate 50 11 in the above described operative assembled relation to the handle member 6 and abrading element 10, a fastener, such as the staple 12, is driven downwardly through the depressed centrally seated portion 15 of the 55 keeper plate and into the body of the handle member.

From the above description and an inspection of the drawings, it will be apparent that the abrading element 10 will be securely clamped to the handle member around the entire periphery of the end of the latter, so that the same will not wobble or unseat itself in use. Furthermore, the uniform gripping of the entire inner circumference 60 of the abrading element, reduces any tend-

ency of the fabric of the latter to tear away from the fastening, as is so likely to occur when the fastening is of a type engaging but a single limited portion of the abrading element. A further advantage of the novel 70 construction, as presented by the above described combination, is that the strains upon the staple or other fastening means are distributed in such a manner, that there is little likelihood of such fastening means working 75 loose.

Referring now to Figures 4 and 5 of the drawing, I have shown a slightly modified form of fastening or attaching means, which, nevertheless, embodies the general principles 80 and advantages already pointed out as to the above described preferred form of fastening or attaching means. This modified form of fastening or attaching means comprises, a keeper plate 17 provided with a depending peripheral flange 18, preferably having at its free edge a plurality of serrations 19. The abrading element 10 is assembled against the socketed end of the handle member 6 in the same manner as previously described, and the modified keeper plate 17 is disposed over the abrading element so that its peripheral flange is engaged 90 against the inner circumferential portions of the latter. A fastener of any desired 95 kind, e. g. such as the nail 20 is driven downwardly through the center of the keeper plate 17, and into the body of the handle member 6, while at the same time the keeper plate is driven downwardly into place in the socketed end of the handle member, so that its peripheral flange 18 clamps the inner circumferential portions of the annular abrading element against the marginal portions 100 of the socketed end of said handle member, thus firmly securing the abrading element in operative attached relation to the handle member.

The device, with its convenient and strongly attached handle member, affords a 110 most excellent and efficient scouring implement, for scouring and cleansing various kinds of utensils or the like, and one which provides for a very effective abrading action which quickly and easily removes caked or 115 hardened dirt crusts and the like from all kinds of vessels and utensils.

Having thus described my present invention, I claim:—

1. A scouring implement, comprising an 120 annular spongiform abrading element, a handle member having at one end a socket, and means for attaching the former to the latter consisting of a keeper plate having its central portion seated in said handle socket, the marginal peripheral portions of said keeper plate being engaged over the inner circumferential portions of said abrading element to clamp the same against the marginal portions of said handle socket, and a 125 130

fastener extending through said central portion of said keeper plate into the body of said handle member.

2. A scouring implement, comprising an annular spongiform abrading element, a handle member having at one end a socket, the socketed end of said handle member being externally tapered to provide an acute gripping edge at the outer margin of said socket, and means for attaching said abrading element to said handle member, consisting of a metallic keeper plate having its central portion seated in said handle socket, said keeper plate having a peripheral grip-

ping lip engaged over the inner circumferential portion of said annular abrading element to clamp such portion of the latter against the acute gripping edge of said handle end, and a fastener extending through said central portion of said keeper plate into the body of said handle member.

In testimony that I claim the invention set forth above I have hereunto set my hand this 8th day of May, 1924.

RUSSELL B. KINGMAN.
